Clarke & Raymond

UNITED STATES PATENT OFFICE.

WILLIAM S. RICHARDSON, OF BOSTON, MASSACHUSETTS, ASSIGNOR TO THE BALL AND SOCKET FASTENER COMPANY, OF NASHUA, NEW HAMPSHIRE.

GLOVE-FASTENING.

SPECIFICATION forming part of Letters Patent No. 399,162, dated March 5, 1889.

Application filed May 26, 1888. Serial No. 275,229. (No model.)

To all whom it may concern:

Be it known that I, WILLIAM S. RICHARDSON, of Boston, in the county of Suffolk and State of Massachusetts, a citizen of the United States, have invented a new and useful Improvement in Fastenings for Gloves and other Articles, of which the following is a full, clear, and exact description, reference being had to the accompanying drawings, forming a part of this specification, in explaining its nature.

The invention relates to a fastening for gloves and other articles, one member of which comprises a compressible ball held upon one surface of the material in the cavity of the cap placed upon the other surface of the material, the ball and cap being united, and the other member of which comprises a receiving device consisting, essentially, of a flat plate having an upwardly-extending sleeve or ring, which is drawn in to form an opening somewhat less in size than the size of the ball member when expanded.

Referring to the drawings, Figures 1 to 4, inclusive, represent the cap of the ball member of the fastening; Figs. 5 and 6, the washer used therewith. Figs. 7, 8, 9, and 10 illustrate the manner of making the compressible ball. Figs. 11 and 12 are detail views of the eyelet used in securing it to the cap. Figs. 13 and 14 show another form of compressible ball. Figs. 15 to 18, inclusive, illustrate the ball-receiving member of the fastening; and Figs. 19 and 20 show the two members of the fastening together, Fig. 20 also illustrating the compressible ball as secured to the cap by a tack or single-pronged fastening instead of a cap-eyelet.

A represents the compressible ball member of the fastening. It comprises the compressible ball *a*, held to one surface of the material by the cap *a'* upon the other surface of the material, the ball being united to the cap and the material preferably being drawn into the cavity of the cap by a washer or flange, *a*², placed next the ball. I have represented as one form of compressible ball a hollow ball made from a blank shaped substantially as represented in Fig. 7—that is, it has four oval extensions, which are shaped to produce very nearly a flattened sphere, the four parts or sections being separated from each other suffi-

ciently to permit them to be moved inward toward each other to contract the size of the ball. The ends *b* of these sections are preferably not brought together, and there is a hole, 55 *b'*, formed to receive an eyelet or fastening, extending from the cap and either integral therewith or not, as desired, whereby the spring-ball is secured to the cap.

In Figs. 13 and 14 I have represented a compressible ball, which, preferably, is made from a solid ball by cutting slits across the same, whereby it is divided into four parts or sections. This solid ball has an integral shank, which extends through the hole in the washer 65 and is upset upon the cap.

The ball-receiving member or section of the fastening is made from a blank or plate, *C*, of the shape substantially as shown in Fig. 15. It has formed in it the small hole *c* and the 70 larger hole, *c'*, and the metal about this larger hole is drawn outward or upward from the plate sufficiently to form a sleeve, *c*², the opening *c*³ of which is of the least diameter of its bore. This sleeve is represented as extending upward from the flange *c*⁴, and the fastening has an extension, *c*⁵, which receives the cap-eyelet or other device, *c*⁶, for fastening it to the material. The opening *c*³ is of a size 80 slightly less than the expanded ball, and to secure the parts together the ball is placed in the opening and pressed against the upper edge of the sleeve and contracted or compressed sufficiently to permit it to be forced below the upper edge of the sleeve into the cavity beneath the opening, when it expands automatically, and thus serves to secure the two parts or sections of the fastening together. 85

Having thus fully described my invention, I claim and desire to secure by Letters Patent 90 of the United States—

1. In a fastening device, the member comprising a compressible ball adapted to be placed upon one surface of the material of the glove or other article to which it is attached, 95 and a cap upon the opposite surface of said material, the ball being secured to the cap and held in its cavity by a fastening extending from the ball through the material to the cap, substantially as described.

2. The combination of the member of a fastening, consisting of a compressible ball, *a*, a

cap, a' , held or secured to the material, as described, with the ball-receiving device comprising a plate, C, having a sleeve, c^2 , provided with the opening c^3 , of less size than the size 5 of the ball when expanded, substantially as described.

3. The member of a fastening device for receiving and holding an expansible ball, comprising the plate C, the sleeve c^2 , extending 10 therefrom and having the opening c^3 , of less size than the expanded ball which it receives,

and the ear c^5 , by which it is secured to the material, substantially as described.

4. The combination of the compressible ball a , the cap a' , the crowned washer a^2 , and a stud 15 or eyelet connecting the ball and washer with the cap, substantially as described.

WILLIAM S. RICHARDSON.
